UNITED STATES PATENT OFFICE.

EDWARD JOHN RIDGWAY, OF NEW YORK, N. Y.

DESIGN FOR A PLATE.

49,970.

Specification for Design.

Patented Nov. 28, 1916.

Application filed October 5, 1916. Serial No. 123,989. Term of patent 7 years.

To all whom it may concern:

Be it known that I, EDWARD JOHN RIDGWAY, a subject of the King of Great Britain and Ireland, residing at Staten Island, in the county of Richmond and State of New York, have invented a new, original, and ornamental Design for a Plate, of which the following is a specification, reference being had to the accompanying drawing, forming part thereof.

The figure is a plan view showing a plate having my new design.

I claim:

The ornamental design for a plate, as shown.

EDWARD JOHN RIDGWAY.

Witnesses:

PAUL N. MILLELOT,
E. CROWE.
